AIRCRAFT UNDERCARRIAGE

George Herbert Dowty, Cheltenham, England

Original No. 2,049,109, dated July 28, 1936, Serial No. 50,784, November 20, 1935. Application for reissue July 30, 1937, Serial No. 156,545. In Great Britain July 2, 1934

26 Claims. (Cl. 244—102)

This invention relates to aircraft undercarriages of the retractable type, or to tailwheels of like type, in which the wheels (or floats or skids) and their associated structure are adapted to be retracted towards or into the wings or fuselage, or points adjacent thereto. A primary object of the present invention is the provision of lifting means in the form of a self-contained unit attachable to the aeroplane by one or more pins or like fittings. The invention is more particularly applicable to that type of undercarriage in which one element, for example a strut, is, for the purpose of retraction, adapted to "break" about an axis of articulation between its ends, so that its overall length may in effect shorten. It may be desirable in some cases to provide such an element with means for breaking it or reextending it, which does not require points of anchorage or of application of force external to the element; and means will for the purpose of convenience, be referred to as retracting gear, and it may comprise either a prime mover, or, as is preferred in the present case, some form of slave unit such a jack system, or a mechanism adapted to be driven by an external source of power, by transmission which will be substantially unaffected by the movement of the element. A further object of the present invention is the provision of hydraulic means for retracting undercarriages, adapted to be carried by, and form part of, a strut. In the following description the action which is termed "breaking" is deemed to mean angular movement between two pivotally interconnected or articulated parts, about a centre which is disposed between their ends or points of pivotal attachment to the rest of the structure. In effect it means a sort of knuckle joint action.

According to the invention broadly stated, the retracting gear is carried wholly by the breakable element which it is to control, so that no external mechanism other than the source of energy or controlling gear, is required which can be substantially affected by the movements of the element. In a preferred form of the invention, as applied to a strut which is breakable, the two articulated units consist of two deformable triangular frames, and one side of each triangle is variable in length, for example by comprising wholly or in part a hydraulic jack. Further, according to the invention, a foldable strut for use with retraction gear for aircraft comprises mutually articulated elements and carries means for applying moments about the centre of articulation, the reaction of which means is taken by the strut itself without any external connections

being necessary for the moment applying means. The invention therefore provides a strut element for retractable undercarriages comprising a structure with pivoted joint or joints between its attached ends, and means carried by the structure for applying a moment at the joint or joints for controlling the relative angular position of the articulated parts of the structure. By the employment of the above features it follows that an undercarriage can be retracted without the necessity for additional points of attachment, and without resort to means external to a foldable strut, except, perhaps, the provision of a prime mover or source of energy suitably connected. The invention also includes a construction of strut for retractable aircraft undercarriages in unit form, as will be described hereafter. The invention includes the use of purely mechanical jack retracting gear, driven from an external source, and arranged according to the foregoing statement.

A preferred form of the invention is illustrated diagrammatically in the accompanying drawings, in which:

Figure 1 is a side elevation of the improved strut, parts being broken away and shown in section; and

Figure 2 is a diagrammatic side elevation of the strut in a broken position.

In these figures the strut comprises two shell-like members or sections 1 and 2 of substantially triangular form adapted to meet on a common base line at 3. Towards the apices of these members 1 and 2 are fittings 1A and 2A adapted to be pivotally connected one to a suitable pin fitting on the aircraft, and the other to the axle or other lower part of an undercarriage to be retracted. The elements 1 and 2 are pivotally joined together by a pin or bolt 4 at the axis about which breaking is required. The bolt 4 also carries pivotally a bracket fitting 5 which is again of triangular form. The fitting 5 houses certain parts hereinafter described. Towards the outer ends of the elements 1 and 2 there are provided pins 6 and 7. It is unnecessary to reduplicate the description, so the following describes the parts appropriate to the member 1; the pin 6 carries with slight angular freedom the end fitting 8 which forms a cap for a hydraulic jack cylinder 9 in which there operates a jack piston 10 with a piston rod 11 protruding through the other ends of the cylinder 9, with a suitable slide packing 12. In the cap member 8 there are two pipe connections 8A and 8B for the admission and emission of operative fluid under suitable con-

trol. The piston 10 is a double-acting piston, and the lower end of the cylinder 9 has an inlet passage at 13 connecting it with a pressure pipe 14. The precise nature of the hydraulic arrangement 5 may be suitably varied and forms no part of the invention, but it may be mentioned that since an identical hydraulic jack is provided in the element 2 also, the pipelines such as 14 are suitably connected up with any necessary intermediate 10 lengths of flexible pipe such as indicated at 15, to accommodate breaking of the strut and to allow the slight angular movements of the cylinder 9 for example about the pin 6. Ordinarily 15 it is presumed that the two jacks are identical, and their connections are simple parallel connections. The outwardly projecting end of the piston rod 11 carries a fork fitting 16 carrying in turn a suitably journaled pinion 17 on an axis in the form of a pin 17A. The pinion 17 is rigid with the 20 fork 16, but the fork and pinion are angularly movable about the pin 17A, which supports them in the fitting 5. The pinion 17 constantly meshes with an idle pinion 18, also carried rotatably by the bracket 5; pinion 18 in turn meshes with the like pinion 19, and the pinion 19 finally meshes with a pinion 20 which is attached to the external end of the piston rod 21 belonging to the other hydraulic jack, the cylinder of which is 25 shown at 22. By virtue of this train of pinions 30 it follows that any angular movement of the jack comprising the cylinder 9 and the rod 11 with respect to the fitting 5, necessarily entails like but opposite angular movement of the jack comprising the cylinder 22 and rod 21. Consequently any 35 slight failure of one jack hydraulically, or lag as between one jack and the other, can be corrected by this positive train of engagement. It will be observed that on each side of the common base 3 a triangular structure is present; for example, 40 in the element 1 there is a stress triangle comprising the hydraulic jack as a whole, connecting the axes at 6 and 17A, the fitting 5 connecting the axis at 17A to the axis at 4, and the member 1 itself connecting the axis at 4 to the axis at 6. 45 When the radius rod is fully extended as shown in Figure 1, it may be provided that the contacting edges at 3 of the shell parts 1 and 2 provide a sufficient abutment to take all compression 50 loads between the fittings 1A and 2A, but if this is not convenient, the compression loads may be shared by the members of the triangle above described and the corresponding triangle in the element 2; this is especially so if (as shown in Figure 1) the parts 8, 10 come into mechanical abutment, whereby compression loads are transmitted 55 through the triangles positively, and there need be no hydraulic pressure.

Figure 2 shows how the construction above described effects retraction. If liquid under pressure be introduced for example, through the union 8A (and of course the corresponding union into cylinder 22) the piston rods 11 and 21 are forced outward from the cylinders, consequently 60 applying a moment about the axis at 4, and it will be observed that there is no reaction external to the radius rod as a whole, in that the cylinder 9 acts on the pin at 6 and the rod 11 acts on the pin at 17A. When this takes place the side 65 of the triangle 8/17A is elongated and therefore the member 1 moves angularly about the axis 4; simultaneously of course the member 2 moves symmetrically in opposite sense about the same axis, and the result of such movement is a position shown for example as in Figure 2. The de-

crease in distance between the fittings 1A and 2A in Figure 2 and compared with Figure 1, represents the degree of movement achieved towards retraction. For re-extension of the radius rod, 70 pressure is applied to the jacks by the pipe 14, 5 when the jacks are correspondingly contracted so that the construction returns to the position as shown in Figure 1.

Usually, when the strut is extended as in Figure 1, its external elements 1 and 2 will take the 10 whole of the longitudinal stresses in it, but it may be arranged that these loads be shared, or taken wholly, through the jacks themselves.

In an alternative construction, not illustrated, 15 only one jack is provided and employed, of which the cylinder is pivotally attached to the element 1 and the piston to the element 2, so that extension or contraction of this single jack produces articulate movement of the radius rod; the thrust 20 line of the jack is for this purpose offset from the axis of articulation. Again, if it is not desired to harmonize the action of the two jacks above described positively, the train of pinions 17, 18, 19 and 20 may be omitted. In any case, however, 25 it will be observed that the self-contained retracting gear of the radius rod applies moments for breaking it about its centre of articulation, and the reaction of such moments is taken within the radius rod itself; it will also be appreciated 30 that the device above described comprises self-contained means within a breakable strut for controlling the relative angular positions of articulated parts thereof, that is to say the parts 1 and 2 as above described.

What I claim as my invention is:

1. A strut comprising companion sections, a bracket between adjoining ends of said sections housed by the sections when the sections are in alignment, a pin pivotally connecting both sections with said bracket, and adjusting means for said sections consisting of cylinders extending longitudinally in said sections, pistons working in said cylinders and rods extending from said pistons out of the cylinders and pivoted to said bracket in offset relation to the pivotal connection 45 of the sections with the bracket.

2. A strut comprising companion sections, a bracket between adjoining ends of said sections pivoted to the sections and having end portions 50 extending into the sections when the sections are in axial alignment with each other, a cylinder extending longitudinally in each section and tiltable transversely of the section, and pistons slideable longitudinally in said cylinders having rods extending from the cylinders and pivoted to ends of said bracket.

3. A strut comprising companion sections, a bracket between adjoining ends of said sections pivoted to ends of the sections and having end 60 portions projecting into the sections when the sections are in axial alignment with each other, a cylinder extending longitudinally in each section and mounted for tilting movement transversely of the section, a piston slideable longitudinally in each cylinder, rods extending from said pistons through ends of said cylinders and pivoted to ends of said bracket, and means for transmitting swinging movement from one piston and cylinder to the other piston rod and cylinder.

4. A strut comprising companion sections, a bracket between adjoining ends of said sections pivoted to ends of the sections and having end portions projecting into the sections when the sections are in axial alignment with each other,

5 a cylinder extending longitudinally in each section and mounted for tilting movement transversely of the section, a piston slideable longitudinally in each cylinder, rods extending from said 10 pistons through ends of the cylinders towards said bracket, pinions rotatably carried by ends of said bracket, the piston rods being secured to said pinions and extending radially therefrom, and idler pinions rotatably carried by said bracket and meshing with the first mentioned pinions and each other.

5. In an airplane undercarriage, a pair of sections having adjoining inner ends, a mounting for said sections having inner ends of the sections pivoted thereto intermediate ends of the mounting, cylinders extending longitudinally of said sections and having their outer ends pivoted to the sections for movement transversely thereof, pistons slideable in said cylinders and having rods projecting from inner ends of the cylinders, fluid pressure connections for said cylinders, and means pivotally connecting the piston rods with the ends of said mounting in offset relation to the pivotal connection between the mounting and the inner ends of the cylinders, said piston rods being shiftable by fluid pressure flowing through said connections into the cylinders for shifting the sections with respect to each other.

6. A strut comprising companion sections having inner ends adjacent each other, a mounting pivotally connected intermediate its length to inner ends of the sections, and adjusting means for said sections consisting of cylinders extending longitudinally of the sections and having their outer ends pivotally connected with the sections, and pistons slideable in said cylinders and having rods extending from inner ends of the cylinders and pivoted to ends of said mountings in offset relation to opposite sides of the plane of the pivotal connection of the sections with the mounting.

7. A strut comprising companion sections, a mounting between adjoining ends of the sections pivoted intermediate its length to ends of the sections, and a hydraulic jack including a cylinder extending longitudinally of each section, a piston slideable longitudinally in each cylinder and having a rod extending from one end of the cylinder, one end of the hydraulic jack being pivotally connected to the section and the other end being pivotally connected to the mounting in offset relation to opposite sides of the plane of the pivotal connection of the sections with the mounting.

8. A strut comprising two companion sections formed to engage each the other when aligned, whereby to be self-resistant to compression load between their remote ends, a pivot joint joining adjacent ends of said sections, pivot joints at the remote ends of said sections for attaching the strut to aircraft parts, and jack means, wholly carried by the strut, for causing relative angular movement of said sections.

9. An aircraft strut for connecting two relatively movable parts of an aircraft structure, comprising two articulated sections adapted for connection at two points, one at one end of the strut to one such part of the aircraft structure, and the other at the remote end of the strut to the second part of the aircraft structure, said points of connection being so located that a line joining them, when the sections are aligned, passes to one side of the axis of articulation, means carried wholly upon the strut, reacting from one

section to the other, to break the strut, and to swing the points of connection to the opposite side of the axis of articulation, or to return the sections to alignment from such broken position, and means movable with each section, formed and proportioned to contact with the corresponding means movable with the other section, when the sections are aligned, to positively transmit thrust from one section to another, without reliance on the strut-breaking means.

10. A strut comprising two sections pivotally connected and relatively movable about such pivot into and from alignment, and formed for connection at their respective swinging ends to two relatively movable parts of an aircraft structure, means carried wholly by such strut for effecting such swinging movement of the sections, and two cooperating thrust-transmitting means, one movable with one section and the other with the other section, formed to contact when the sections are in alignment, thereby to constitute the primary means to transmit compression loads from one such aircraft part to the other.

11. An aircraft strut comprising two relatively movable sections each adapted for connection at a single point to one of two aircraft parts which are relatively movable to effect movement of such points along a line towards and from each other, means guiding the sections for relative movement which has a component transversely of such line, and means carried wholly by the strut for so moving the sections.

12. An aircraft strut comprising two hollow shells of generally triangular form in elevation, a pivot pin connecting said shells at one angle for relative swinging movement towards and from alignment, each shell being formed, at its swinging end, for connection to an aircraft part, and power means enclosed wholly within a shell, and reacting from the other shell, for effecting relative swinging movement of the shells.

13. In a retractable aircraft undercarriage, the combination of a generally hollow structural component adapted to break about an axis of articulation between its ends, and retracting means disposed within said hollow component so as to produce reaction between the articulated parts thereof, and to produce a breaking moment about said axis.

14. For retractable undercarriages for aircraft, a hollow strut comprising in combination articulated sections, each section comprising a deformable triangular frame, and such frames of the two sections having one side in common, and a jack enclosed within the hollow strut and forming another side of each such triangle, whereby such triangle is deformable to produce articulated movement of the sections of the strut.

15. An aircraft strut comprising two sections which are substantially triangular in elevation, a pivot pin connecting the two sections at an acute angle of each, for relative swinging movement to and from an aligned position, wherein their bases adjoin and a line connecting their apices intersects the bases, said sections, at their apices, being formed for connection respectively to one of two relatively approachable aircraft parts, and means carried wholly by the strut for effecting such relative swinging movement of the sections.

16. An aircraft strut comprising two sections which are substantially triangular in elevation, a pivot pin connecting the two sections at an acute angle between the base and a side of each,

- for relative swinging movement to and from an alined position, wherein a line connecting their apices intersects their bases, and their bases contact to transmit compression loads from one apex 5 to the other along such line, said sections, at their apices, being formed for connection respectively to one of two relatively movable aircraft parts, and means reacting wholly from one section to the other for effecting such relative 10 swinging movement of the sections.
17. An aircraft strut comprising two articulated sections, and formed at its ends for connection to two relatively approachable aircraft parts, the axis of articulation being located, when 15 the sections are alined, at one side of a line of thrust connecting said ends, hydraulic jack means carried wholly by said strut to break the same, and thereby to move the ends so that a line connecting them lies on the opposite side of such 20 axis, said jack means including two relatively movable elements so formed as to contact each other, when the sections are alined, thereby to constitute positive thrust-transmitting elements in such position of parts.
18. An aircraft strut including two sections, and formed at its opposite ends for pivotal connection to two relatively movable aircraft parts, and a pivot pin connecting the two sections and disposed parallel to one of the terminal pivotal 30 connections, and means carried wholly by the strut, and reacting between the sections, to produce a moment about said pivot pin, thereby to effect approach of the two terminal pivotal connections.
19. An aircraft strut comprising two pivotally connected terminal elements and an intermediate element, the two terminal elements, when in normal position, being substantially alined to transmit forces from the outer end of one to the 40 outer end of the other, and means reacting from the intermediate element and between the two terminal elements to produce a torque about their pivotal connection, thereby to effect approach of such outer ends of the terminal elements, and to lessen the effective length of the strut as a 45 whole.
20. An aircraft strut comprising two terminal elements and an intermediate element, the two terminal elements, when in normal position, being substantially alined to transmit forces from the outer end of one to the outer end of the other, and means reacting from the intermediate element, in a direction transverse to the strut as a whole, to effect approach of such outer ends of 55 the terminal elements, thereby to lessen the effective length of the strut as a whole.
21. An aircraft strut comprising two terminal elements and an intermediate element, the two terminal elements, when in normal position, being substantially alined to transmit forces from the outer end of one to the outer end of the other, and means carried wholly by one of the terminal elements and reacting from the intermediate element to effect approach of such outer ends of 65 the terminal elements, thereby to lessen the effective length of the strut as a whole.
22. An aircraft strut comprising two terminal elements and an intermediate element, the two terminal elements, when in normal position, being substantially alined to transmit forces from the outer end of one to the outer end of the other, and means carried wholly by each of the terminal elements, and reacting from the intermediate element to effect approach of the outer ends of the terminal elements, thereby to lessen the effective length of the strut as a whole. 10
23. An aircraft strut, to effect approach or recession of two relatively movable aircraft elements by lessening or increasing, respectively, the effective length of such strut, comprising two articulated sections pivotally connected to each other, each by an end, a pivot connection formed at the remote end of each section, for securement to one of such aircraft elements, and force-producing means carried wholly by the strut, and organized and arranged to react only between the two sections, to produce a moment about the axis of articulation, and thereby to move the sections from a position of substantial alignment to a folded position, or vice versa. 15
24. An aircraft strut, for connecting an aircraft fuselage or the like and a relatively movable undercarriage, comprising two parts pivotally connected intermediate the ends of the strut as a whole, and a pin fitting carried by each such part for interconnection to a complementary fitting on the aircraft structure and undercarriage, respectively, and constituting the sole supporting connection of the strut thereto, means carried wholly by the strut to exert a torque about the pivotal interconnection between the two parts, and distant means on the aircraft structure for the control of the preceding means. 20
25. An airplane landing gear strut, comprising two companion sections, a pivot joint joining adjacent ends of said sections for relative pivotal movement, a pivot pin defining an axis parallel to said pivot joint at the remote end of each section, constituting the sole means for attachment of the strut to relatively movable aircraft parts, and jack means wholly carried by the strut for causing relative angular movement of said sections. 25
26. An airplane landing gear strut, comprising two companion sections, a pivot joint joining adjacent ends of said sections for relative pivotal movement, a pivot pin defining an axis parallel to said pivot joint at the remote end of each section, constituting the sole means for attachment of the strut to relatively movable aircraft parts, hydraulic jack means wholly carried by the strut and reacting solely between the two sections, for causing relative angular movement of said sections about said pivot joint, and consequent rotation of each section about its terminal pin, and a pressure line for connecting the jack means to a distant pressure source, and constituting the sole jack-operating means which extends exteriorly of the strut. 30
